UNITED STATES PATENT OFFICE.

ENRIQUE G. DOERING HARMSEN, OF HACIENDA SAUSAL, VIA TRUJILLO, AND
MATHEW KALAFATOVIC, OF CUZCO, PERU.

SAFETY BOX.

Application filed December 10, 1920 Serial No. 429,799

To all whom it may concern:

Be it known that we, ENRIQUE G. DOERING HARMSEN and MATHEW KALAFATOVIC, citizens, respectively, of Peru and Austria, 5 and residing, respectively, at Hacienda Sausal, via Trujillo, Peru, and Cuzco, Peru, have invented new and useful Improvements in Safety Boxes, of which the following is a specification.

10 Our invention relates to safety packing boxes and is intended to provide a receptacle into which may be packed coin, bullion, jewelry or other kinds of valuable articles or goods, for transportation with little danger of subtle subtractions or substitutions 15 of the contents.

Another object of our invention is to construct a box having parts of its structure transparent and easily accessible whereby 20 the contents of the box are immediately visible. At certain stages of the transportation or handling the shipment may be checked without unpacking and with practically no loss of time.

25 A further object of our invention is to provide a packing box of substantial and economical construction and one that will give the utmost security to the consignor, carrier and consignee.

30 The construction of boxes specially adapted for the use of traveling agents and jewelers for readily displaying their wares is also contemplated.

Other objects of our invention are pointed 35 out and described in the description contained in the specification that follows.

Reference is made in this specification to the accompanying drawings in which like numerals represent corresponding parts.

40 Figure 1 is a perspective view of a box constructed according to our invention, the cover being shown in open position;

Figure 2 is a perspective view of the bottom of the box;

45 Figure 3 is a perspective view of one end of the box;

Figure 4 is a perspective view showing one of the lid strips and the grooves formed therein;

50 Figure 5 is a plan view of the box with the cover removed and parts in section;

Figure 6 is a longitudinal vertical section through the center of the box showing the cover in locked position;

Figure 7 is a transverse sectional view 55 with the cover in closed position; and

Figure 8 is a cross section through one corner of the box showing the cover in closed position.

The box constituting the subject matter 60 of this invention is preferably composed of units which can be readily assembled and disassembled. The principal units are the bottom or base 10, the end pieces 14, the lid strips 15, the transparent plates 30, 31 65 and the perforated metallic plates or gratings 35, 36.

The base or bottom 10 as shown, is rectangular in shape and is formed near each of 70 its four corners with holes 13 adapted to receive the tubular bolts 21 (see Fig. 8). The holes 13, at the underside of the base 10, are enlarged to a suitable depth so that the ends 22 of the tubular bolts, when the bolts are in position, will be flush with 75 the lower surface of the base. The longitudinal sides of the base 10 are cut way to a depth equal to about one-fourth of the thickness of the wood over the greater part 80 of the length of such sides and a holder in the form of a strip of steel, iron, brass or other suitable material, having two parallel grooves 11, 12 formed or cut therein, is placed and secured in each recess.

One of the end pieces employed is illustrated in Figure 3 and it will be understood 85 that the opposite end piece is of similar construction. The end piece 14 is preferably a rectangular piece of wood in which are bored 90 the vertically extending holes 13' 90 adapted to register with the holes 13 of the base and receive the tubular bolts 21. The upper corners of the end pieces are cut away to an extent sufficient to fit the lid strips 15 when the latter are in position. This 95 leaves the upwardly projecting central piece 23 which is recessed throughout its length near its juncture with the body portion of end piece 14. In this recess is fitted and secured a strip which forms with the 100 upper and lower walls of said recess a pair of parallel grooves 19, 20. A rectangular recess is also cut along each inner edge of the end pieces 14 and a holder 16 having spaced parallel grooves 17, 18 is secured 105 in each of these recesses.

The lid frame of the box consists of two similar strips 15 having holes 13" formed

near each end adapted to align with holes 13 and 13' and receive the tubular bolts 21, washers 25 and fastening screws 24 (see Fig. 8). The tubular bolt 21 is internally threaded and the frame of the box is firmly held together by the screws 24 which fit the corresponding threads of the tubular bolt. The holes 13" are counter-sunk to a sufficient depth to allow the heads of the fastening screws 24 to be entirely hidden by the seals 37. Each lid strip is recessed at right angles and each recess is fitted with metallic strips having parallel grooves 26, 27 and 28, 29.

In assembling the box two of the tubular bolts are inserted through the holes 13 and 13' thereby positioning the base and one of the end pieces. The transparent plates 30 are then placed in the grooves 12 and 18 which are now at right angles and in the same plane. The perforated steel plates or gratings 35 are likewise inserted in the outside grooves 11 and 17. The lid strips 15 are placed in position with the holes 13" at one end engaging the two bolts 21 which have been inserted through the base and end pieces. The plates 31 and 36 are placed in the grooves 29 and 28 of the lid strips and pushed through these grooves until they engage the corresponding grooves of the end piece 14. The material to be shipped, such as bullion, is now placed within the box and the closure end 14 is placed in position so that its grooves engage both the side and top plates. The two remaining bolts 21 are then inserted through the registering holes 13, 13' and 13". The screws 24 are turned and their threaded connection with the tubular bolts serves to tighten them against the washers 25 and hold the frame work rigidly together. Finally sealing wax is applied about the screw-heads, thereby forming the seals 37 and the box is fully prepared for shipment. It will be noted that when the box is securely closed its contents remain in full view of the interested parties and it cannot be opened without breaking the seals and partially disassembling.

The steel strips above referred to are preferably secured to the frame by screws inserted through said strips into the parts of the box to which said strips are secured so that when the box is built up these screws are not accessible.

The box may have an auxiliary cover if desired, such as indicated by numeral 40. The cover comprises a top 41 for covering the top of the box and two side pieces 42 for covering the sides, thereby hiding the contents of the box from view when the cover is closed and furnishing a further protection from external injury. The top 41 and sides 42 are secured together in any convenient manner as by screws or nails and the top is connected to one of the end pieces 14

by hinges 39. The opposite end 14 of the box is provided with a staple 43 adapted to engage a hasp 38 pivotally secured to the cover 40 so that the cover may be locked in closed position by a pad-lock 44. The box is also equipped with handles 45 pivotally secured to each end piece 14 so that the box can be handled easily and carried without injury. For convenience each box may also have attached to the outside cover or other suitable place a small plate 46 on which the exact weight of the empty box is marked.

It is evident that many modifications of the box illustrated may be constructed. For instance, some of the transparent plates may be omitted if the articles within the box are in such large pieces that they cannot pass through the apertures of the protecting plates. Further, the top grating may be omitted when used in conjunction with a cover, which structure will give ready access to the interior of the box by removing one lid strip and also afford a clearer view of the contents. Such a box or case is specially adapted for the use of traveling agents and jewelers since when closed the valuable contents are hidden from view while upon removing the cover the exhibits are readily visible. The box frame may also be constructed of material other than wood, such as steel, leather, or any other material that is best suited for the goods to be handled.

As the contents of the box can be seen at will, any person who receives it in due course of business is enabled to see with slight examination that the contents are really what they purport to be, so that previous substitutions or subtractions may be readily detected. If it is found at a station that substitution has taken place or the contents have been otherwise tampered with circumstances would naturally point to the person who had charge of the box before this fact was reported.

As stated above, each box is marked with the exact weight when empty which may be assumed in this case to be three kilograms. Assume also that on weighing the same box containing pounds sterling a weight of 8.5 kilograms is found, then the weight of the gold contents is 5.5 kilograms net and assuming that the weight of each coin is 7.5 grams, the contents of the box should be 733 pounds sterling. When the box is to be used for the shipment of standard articles of uniform weight a table 47 is attached to the inside of the cover or to the frame of the box giving the exact weight of the different articles or coins and the quantity of such units in the box can be rapidly ascertained as above illustrated.

This checking by visual examination and net weight enables the parties involved to refuse to receive the box if it is not exactly what it should be, or to note on the receipt

the actual condition or contents when the articles are standard and uniform.

It may be noted that the box may be readily disassembled into units and thus returned to the point of shipment, thereby occupying less cargo space than if shipped empty in built-up condition.

Having described our invention, what we claim as new and desire to secure by Letters Patent, is:—

1. A packing box having a rigid frame, transparent plates inserted in the frame and gratings for protecting said plates.

2. A packing box having a frame comprising a base, end pieces and lid strips securely connected together; transparent side plates supported by said frame and a transparent top-plate maintained in position by said lid strips.

3. A packing box having frame members comprising a base, end pieces and lid strips; transparent side plates supported by said frame members, a transparent top-plate maintained in position by said lid strips, internally threaded tubular bolts, and screws engaging the threads of said bolts for firmly holding the frame members together.

4. A packing box having a frame of opaque material, transparent side plates and

a top plate inserted in the frame, a cover hinged to said frame and provided with depending side pieces adapted when the cover is in closed position to conceal and protect said plates, and means for locking the cover in closed position.

5. A packing box comprising a plurality of members each having inner and outer parallel grooves, transparent plates located in said inner grooves, perforated protecting plates positioned in said outer grooves and means for retaining said members firmly together.

6. A packing box comprising a plurality of recessed members, a metallic strip having inner and outer grooves secured in each of said recesses, transparent plates located in said inner grooves, perforated protecting plates positioned in said outer grooves and means for retaining said members firmly together.

7. A packing box having a frame of opaque material, transparent plates inserted in the frame and a cover hinged to said frame adapted when in closed position to conceal and protect said plates.
